UNITED STATES PATENT OFFICE.

WILLIAM L'E. MAHON, OF ANN ARBOR, MICHIGAN.

EXCAVATING-DIPPER TOOTH.

1,133,234.

Specification of Letters Patent. Patented Mar. 23, 1915.

Application filed July 15, 1911. Serial No. 638,706.

To all whom it may concern:

Be it known that I, WILLIAM L'E. MAHON, a citizen of the United States of America, residing at Ann Arbor, in the 5 county of Washtenaw and State of Michigan, have invented certain new and useful Improvements in Excavating-Dipper Teeth, of which the following is a specification, reference being had therein to the accompanying drawings.

The invention relates to excavating or dredging dippers and more particularly to the construction of tooth employed thereon.

It is the object of the invention to obtain 15 a construction of tooth having renewable point and which has substantially the same strength and rigidity as an integral construction.

To this end the invention consists in the 20 peculiar construction, arrangement and combination of parts as hereinafter set forth.

In the drawings,—Figure 1 is a side elevation of the tooth; Fig. 2 is a plan view thereof; Fig. 3 is a plan of the forward end 25 of the tooth base with the point removed; Fig. 4 is a longitudinal section through the detachable point; and Fig. 5 is a rear elevation thereof.

My improved construction of tooth is applicable to any standard construction of excavating dipper and may be arranged thereon in the usual manner. The drawings therefore show only the detached tooth which is constructed as follows: A is the shank portion or tooth base which is adapted to fit 35 over the bottom of the dipper, and B is an underlip portion for engaging the under face of said bottom. C is the point or tooth proper which projects forward beyond the 40 edge of the dipper bottom and forms a chisel edge for penetrating the material to be excavated.

It is obvious that the point of the tooth is subject to continual wear which necessitates 45 sharpening or renewing from time to time. At the same time the stresses to which it is subjected are such that where formed of a separate member from the tooth base it is difficult to obtain the requisite strength and 50 rigidity. Thus there are vertical stresses

which tend to break off the point from its base, and lateral stresses which tend to deflect it to one side or the other.

My improved construction is designed to provide an engagement between the tooth 55 base A and a detachable tooth point C which will provide for the various stresses to which the point is subjected, imparting substantially the same rigidity to the tooth as in the integral construction.

In detail, the forward end or portion E 60 of the tooth base A is of a tapering or V-form adapted to engage a correspondingly fashioned recess in the tooth point C. At the end of the portion E is a dowel shaped 65 projection F engaging a socket G in the tooth point C, while the portions of said tooth point upon opposite sides of the V-shaped recess are provided with dowel shaped projections H which engage recesses 70 I in the tooth base. Thus the seat for the tooth point is provided with a three-point bearing, the dowel shaped projections H serving to hold the inner end of the tooth point both from lateral and from spreading 75 movement, and the dowel shaped projection F also holding said point from displacement laterally. Furthermore, the tapering seat formed by the V-shaped portion E of the tooth base will take up all lost motion and 80 will impart rigidity to the structure.

For holding the parts together the engaging portions of the tooth point and tooth base are provided with a vertically extending recess therethrough, through which a 85 bolt J is passed, the ends of said recess being enlarged at K and L to receive the head and nut of the bolt.

A structure formed as described is one 90 which permits of renewing the tooth point whenever necessary, it being merely necessary to disengage the bolt J which permits of disengaging the point and replacing by another. When secured in position, and during the operation of the dipper the tooth 95 point is rigidly held.

What I claim as my invention is:

An excavating tooth, comprising a base and a point, and means establishing the same in a rigid relation, the base having a 100

tapering portion fitting within a similarly shaped socket in the point, the point being formed with opposite tongues within the socket, which are received by grooves in opposite faces of the tapering portion of the base, a dowel being projected rearwardly from each tongue and received by a socket in the base, said dowels being parallel.

In testimony whereof I affix my signature in presence of two witnesses.

WILLIAM L'E. MAHON.
